PROCESS OF CRACKING PETROLEUM

Filed Dec. 21, 1925

UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS OF CRACKING PETROLEUM

Application filed December 21, 1925. Serial No. 76,640.

This invention relates to improvements in process of cracking petroleum, and refers more particularly to that type of process in which the oil is passed through a heating coil and thence into suitable expansion chambers, the vapors removed therefrom and subjected to reflux condensing action.

The feature of the present invention consists, in one process, in subjecting the raw oil, 10 the residuum and the reflux condensate to independent cracking conditions of temperature and pressure, delivering them each to their own expansion chamber, and then passing the vapors preferably to a common dephlegmator. The residuum from each expansion chamber is collected and returned to the residuum coil for treatment, while the reflux condensate from the dephlegmator is likewise collected and returned to the coil adapted 20 for heating the reflux condensate.

In order to more clearly understand the invention I have shown the accompanying drawing, in which the single figure is a diagrammatic view, partly in side elevation and 25 partly in vertical section, of an apparatus in which my invention may be carried out.

Referring to the drawing, 1 designates the furnace in which are mounted the heating coils 2, 3 and 4 respectively. In the present 30 instance they are shown as in one furnace, although it is obvious that separate furnaces may be used if it is desired to more effectively control the temperature of the coils independently of each other. The coils are provided 35 with respective transfer lines 5, 6 and 7, having throttle valves 8, 9 and 10, leading to the respective expansion chambers 8', 9' and 10'. The raw oil is delivered to the coils 2 by the feed pump 11 connected to any suitable source 40 of raw oil supply, as, for example, gas oil, fuel oil or crude. The reflux condensate is delivered by pipe 13 and reflux pump 12 to the inlet side of the coil 3. The residuum is drawn off from each expansion chamber 45 through the pipes 14, each controlled by valve 15 to a header pipe 16, which in turn connects to pipe 17 through the pump 18, whereby residuum may be delivered to the inlet side of the coil 4. Some of the residuum 50 may be drawn off elsewhere from each of the

expansion chambers through the pipes 19 controlled by valves 20. Likewise some of it may be bypassed out through the header, through branch pipe 21, by suitably controlling the valves 22 and 23. Some of the reflux 55 may be bypassed through the branch pipe 24 by suitably controlling the valves 25 and 26.

Vapors pass out of respective expansion chambers through the vapor outlet pipes 27 each controlled by throttle valve 28, to a 60 common header vapor line 29, leading to the lower side of a dephlegmator 30. Some of the vapors may be independently bypassed through the branch lines 31 by suitably controlling the valves 32 and 33. In the event, 65 however, that the vapors are bypassed from the expansion chamber 10' it will be desirable to have a bypass line 34 provided with suitable valves 35, which is connected with the header 29. 70

The reflux condensate is drawn out of the bottom of dephlegmator through pipe 13, while the vapors pass out of the top of the dephlegmator through vapor pipe 36, having throttle valve 37, and are led into condenser coil 38 thence to receiver 39. This receiver 39 is provided with gas outlet pipe 40, having throttle valve 41, and liquid draw-off pipe 42, having throttle valve 43. 75

The process may be operated as follows: 80 The charging stock, say, for example, fuel oil, may be heated in the coil 2 to a transfer temperature of, say, 825° F., more or less and maintained under a pressure of say, 800 pounds more or less in the coil 2 and expansion chamber 8'. The reflux condensate may be heated to a transfer temperature of say 900° F., more or less and maintained under a pressure of say, 1000 pounds more or less in the coil 3 and expansion chamber 85 9'. The residuum may be heated to a transfer temperature of say, 800° F. more or less and maintained under a pressure of say 600 pounds in the heating coil 4 and expansion chamber 10'. The pressure is controlled by 90 suitably regulating the valves 28 controlling the entrance of vapors to the dephlegmator, which is maintained under a pressure of say, 200 pounds, as may be the balance of the system to the receiver. If desired, the process 95 100

may be so operated that the vapor contents from any of the expansion chambers may be in whole or in part by-passed and delivered elsewhere.

5 By means of the present process, it will be seen that the raw oil, the residuum and the reflux, which are best cracked under different conditions of temperature and pressure, are subjected to their most advantageous 10 conditions of cracking, all in the same process, and as a continuous operation.

I claim as my invention:

1. A process for cracking hydrocarbon oil, comprising initially subjecting charging oil 15 to given cracking conditions of temperature and pressure, permitting the heated oil to undergo conversion in an enlarged zone, subjecting vapors evolved from the initially treated oil to dephlegmation, whereby a substantial quantity of reflux condensate is 20 formed, separately and independently subjecting oil unvaporized by said initial cracking conditions and the reflux condensate formed as a result of said dephlegmation to further cracking conditions of temperature 25 and pressure, such as will effect further conversion thereof and commingling the vapors released from said unvaporized oil and said reflux condensate as a result of said separate 30 independent treatments with the vapors evolved from the charging oil as a result of said initial treatment.

2. A process for cracking hydrocarbon oil, comprising initially subjecting charging oil 35 to given cracking conditions of temperature and pressure, permitting the heated oil to undergo conversion in an enlarged zone, subjecting vapors evolved from the initially treated oil to dephlegmation, whereby a substantial quantity of reflux condensate is 40 formed, separately and independently subjecting oil unvaporized by said initial cracking conditions and the reflux condensate formed, as a result of said dephlegmation to further cracking conditions of temperature 45 and pressure, such as will effect further conversion thereof, permitting such separately treated unvaporized oil and reflux condensate to accumulate in independent bodies, 50 taking off vapors from said independent bodies, and uniting regulated quantities of the unvaporized constituents from said bodies with said oil unvaporized by said initial cracking conditions.

3. A process for cracking hydrocarbon oil, comprising initially subjecting charging oil to given cracking conditions of temperature 55 and pressure, permitting the heated oil to undergo conversion in an enlarged zone, subjecting vapors evolved from the initially treated oil to dephlegmation, whereby a substantial quantity of reflux condensate is 60 formed, separately and independently subjecting oil unvaporized by said initial cracking conditions and the reflux condensate

formed as a result of said dephlegmation to further cracking conditions of temperature and pressure, such as will effect further conversion thereof, permitting said independently treated unvaporized oil and reflux condensate to accumulate in separate bodies, taking off vapors from each of said bodies, subjecting such vapors to reflux condensation, uniting the reflux condensate separated from such vapors with the reflux condensate separated from the vapors evolved from the initially treated oil for further treatment therewith.

GUSTAV EGLOFF.
